UNITED STATES PATENT OFFICE.

NOAH W. HOLT, OF BUFFALO, NEW YORK.

ROLLER-MILL.

SPECIFICATION forming part of Letters Patent No. 286,440, dated October 9, 1883.

Application filed March 13, 1883. (No model.)

To all whom it may concern:

Be it known that I, NOAH W. HOLT, of the city of Buffalo, in the county of Erie and State of New York, have invented new and useful 5 Improvements in Roller-Mills, of which the following is a specification.

This invention relates to an improvement in that class of roller-mills which are employed in the reduction of grain and other similar 10 substances, and has for its object to provide means for separating the rollers, when necessary in starting and stopping the mill, without disturbing the adjustment of the rollers, and at the same time permit both bearings of 15 the movable roller to be finely adjusted both simultaneously and separately.

My invention consists of the mechanism whereby these results are attained, and which will be hereinafter fully set forth, and pointed 20 out in the claims.

In the accompanying drawings, consisting 25 of two sheets, Figure 1 is an end elevation of a portion of a roller-mill to which my improved adjusting mechanism is applied. Fig. 2 is a top plan view of the adjusting mechanism, with parts of the roller-mill in section. Fig. 3 is a side elevation of the adjusting mechanism. Fig. 4 is a vertical section in line *x x* of Fig. 2. Fig. 5 is a sectional view, 30 on an enlarged scale, in line *y y*, Fig. 1.

Like letters of reference refer to like parts in the several figures.

A A' represent the two rollers of the roller-mill; *a a'*, the journals of the rollers, and *a²* 35 *a³* the bearings in which the journals turn. The bearings *a² a³* are made adjustable toward and from the roller *A'*, to regulate the distance between the working-faces of the rollers.

B represents the frame of the roller-mill, 40 and *b* the horizontal ways on which the bearings *a² a³* are moved toward and from the roller *A'*.

c is a horizontal screw-bolt, which engages 45 with its inner threaded end in a threaded opening in the bearing *a²*; and which passes through a horizontal sleeve, *d*, and is provided at the outer end of the said sleeve with a hand-wheel, *D*.

e represents a spiral or other suitable spring, 50 which surrounds the screw-bolt *c*, and which is interposed between the bearing *a²* and a nut,

e', applied to the inner portion of the sleeve *d*, the latter being provided with an external screw-thread for that purpose.

F represents a screw-threaded sleeve, which 55 surrounds the threaded sleeve *d*. The sleeve *F* is screw-threaded both externally and internally, the two threads being cut in opposite directions, the inner thread engaging with the external thread of the sleeve *d*, and 60 the outer thread with an internal thread cut into a lug, *f*, cast with or secured to the frame *B*. As shown in the drawings, the external thread of the sleeve *d* is a left-hand thread and the external thread of the sleeve *F* is a 65 right-hand thread. The spring *e* presses the bearing *a²* toward the roller *A'*, and holds the hand-wheel *D* against the outer end of the sleeve *d*. By turning the hand-wheel *D* the bearing *a²* is adjusted toward or from the 70 roller *A'*.

g is an arm secured to or formed with the sleeve *F*, for turning the same in the threaded socket *f*. By turning the sleeve *F* in one or the other direction it is moved toward or from 75 the roller *A'*, and the sleeve *d* not only follows these movements of the sleeve *F*, but receives an additional axial movement in the same direction by the engagement of the internal thread of the sleeve *F* with the external 80 thread of the sleeve *d*, so that if both threads are of the same pitch the axial movement of the sleeve *d* will be twice as long as that which is produced by the movement of the sleeve *F* alone. The sleeve *d* is held against axial rotation by the pressure of the spring *e* against the nut *e'*. In moving the bearing *a²* toward or from the roller *A'*, by turning the sleeve *F* in the threaded lug *f*, the relative position of the threaded sleeve *d*, nut *e'*, spring *e*, and 85 bearing *a²* remains undisturbed, so that this movement is effected irrespective of the adjustment which is due to the position of these parts, and without distending or compressing the spring *e*.

Each of the bearings *a²* is provided with the adjusting contrivances just described, and the two arms *g* of the adjusting contrivances at both ends of the movable roller *A* are connected by a rod, *h*, whereby both devices can 90 be moved simultaneously, so as to effect the same adjustment at both ends of the roller at

the same time. The rod h is moved by a hand-lever, I , which is pivoted to the frame B at i , and connected with the rod h by a rod, j . The rod j is connected with the rod h by a 5 collar, k , which surrounds a sleeve, L . The latter is provided with an internal screw-thread, which engages with an external thread cut on the rod h . In order to facilitate the application of the threaded sleeve L to the 10 rod h , the latter is divided in the sleeve, as represented in Fig. 5.

The collar k is seated between shoulders l and l' on the sleeve L , which permits the sleeve L to turn in the collar and compel it to follow 15 the movements of the collar in the direction of the rod h . If the rollers are in their working position when the lever and connecting parts are in the position indicated in full lines in Fig. 1, the roller A will be separated from the 20 roller A' by swinging the lever into the position indicated by dotted lines. The movement of the lever I is transmitted by the rods j and h to the arms g of the adjusting devices, and causes the same movement in the bearings a^2 . 25 When the parts are in the position shown in full lines in Fig. 1, with the rollers in their working position, the lever I rests upon the adjacent sleeve d , and the point at which the rod j is connected with the lever I lies in or 30 below a straight line drawn from the fulcrum of the lever I to the point at which the rod j is attached to the rod h , whereby the parts are securely locked in this position. The movement of the lever I is arrested when it reaches 35 the position shown in dotted lines in Fig. 1, by a nose, m , of the lever coming in contact with a stop, m' , on the frame B . Upon turning the threaded sleeve L in the collar k , the rod h receives an axial movement in one or 40 the other direction, which movement is transmitted by the arms g to the sleeves d , and whereby both bearings are simultaneously adjusted. By turning the hand-lever I the rollers are separated for starting and stopping the 45 mill. By turning the threaded sleeve L both bearings are simultaneously adjusted, and by turning either of the hand-wheels D each bearing is separately adjusted, and each of these 50 adjustments or movements is affected without disturbing any of the existing other adjustments. The pressure of the adjusting-screws is exerted in the direction in which the roller-bearings a^2 move and in parallel lines at both ends of the roller A , thereby preventing 55 binding of the adjusting parts. The springs e are not compressed when the rollers are thrown apart, and the rollers can therefore be left in this position for a long period of time 60 without in any manner affecting the tension of the springs.

The roller-bearing a^3 is provided with an eccentric adjusting-piece, n , seated in a recess, n' , in the bearing a^3 below the lining o , in which the journal a' turns. The upper face of the 65 adjusting-piece n is made concentric with the

lining o , and the lower face is made eccentric thereto, as shown in Fig. 4. The adjusting-piece n is adjusted and held in position by set-screws p and p' . Upon moving the adjusting-piece n in one or the other direction, after 70 loosening the bolts q , which secure the cap of the bearing to the body thereof, the lining o is slightly raised or lowered. By this means a very fine vertical adjustment can be effected at either end of the roller A . 75

I claim as my invention—

1. The combination, with the bearings of the movable roller, of mechanism whereby each bearing can be separately adjusted, mechanism whereby both bearings can be simultaneously adjusted, and mechanism whereby both bearings can be moved simultaneously to separate the rollers without disturbing the adjustment of the bearings and without compressing the springs applied to said bearings, substantially as set forth. 80

2. The combination, with a bearing, of an adjusting-bolt, c , an externally-threaded sleeve, d , a spring interposed between the bearing and a shoulder on the sleeve d , a lug, f , 90 and an adjustable sleeve, F , through which the sleeve d passes, and which produces an axial movement of the sleeve d and connecting parts by its rotary movement, substantially as set forth.

3. The combination, with the bearings of the movable roller, of the screw-threaded bolts c , threaded sleeves d , springs e , interposed between said bearings and shoulders on the sleeves d , sleeves F , connecting with the threaded sleeves d , and provided with arms g , and a connecting-rod, h , whereby the sleeves F at both ends of the roller are operated simultaneously, substantially as set forth. 95

4. The combination, with the sleeves F and 100 adjusting contrivances connecting said sleeves with the bearings of the movable roller, of arms g , connecting-rod h , and means, substantially as described, whereby said connecting-rod can be moved in either direction for adjusting both bearings of the movable roller simultaneously, substantially as set forth. 110

5. The combination, with the bearings of the movable roller, of the sleeves F , provided with arms g , means whereby said sleeves are connected with the roller-bearings, threaded connecting-rod h , threaded sleeve L , collar k , connecting-rod j , and hand-lever I , substantially as set forth. 115

6. The combination, with a bearing composed of a body secured to the frame of the machine, and a cap detachably secured to said body, of a loose lining, o , an adjusting-piece, n , constructed with a concentric and eccentric face, and set-screws p p' , substantially as set 120 forth. 125
